UNITED STATES PATENT OFFICE.

JOSEPH LUCCINO, OF BROOKLYN, NEW YORK.

FOLDING CHAIR BED.

1,408,014.

Specification of Letters Patent. Patented Feb. 28, 1922.

Application filed December 23, 1920. Serial No. 432,697.

To all whom it may concern:

Be it known that I, JOSEPH LUCCINO, a citizen of the United States, residing at Brooklyn, in the county of Kings and State 5 of New York, have invented certain new and useful Improvements in Folding Chair Beds, of which the following is a specification.

This invention relates to folding chair 10 beds, and more particularly to an article of furniture of this type, which may be readily and easily converted from a chair into a bed, an object thereof being to provide a chair bed which will be simple in construction 15 and operation, economical to manufacture, durable and serviceable in use and adapted to be converted into a full-length bed with a minimum of effort.

A further object is to provide a folding 20 chair bed having a chair seat pivoted or hinged to the supporting framework at one side thereof and a sectional spring mattress solely supported by the framework adjacent one side thereof, the rear section thereof being suspended or swung from the seat by 25 means of a pair of hangers, the construction being such that the chair may be converted into a bed by swinging the seat rearwardly upon its hinged connection, thus swinging 30 the rear section rearwardly and upwardly and elevating the entire mattress into a partially open position thereby to facilitate the unfolding of the sections.

Other objects of this invention will appear 35 during the course of the description, reference being had to the accompanying drawings forming part of this specification, wherein like reference characters indicate corresponding parts throughout the several 40 figures, and wherein Fig. 1 is a perspective view of a chair bed in its closed position; Fig. 2 is a perspective view of an embodiment of my invention illustrating a step in the operation of unfolding the bed; Fig. 3 45 is a perspective view showing a bed in its unfolded position; Fig. 4 is a side view partly in section illustrating my improved chair bed in its unfolded position, parts being broken away; Fig. 5 is a detail view 50 illustrating various connecting parts.

In its preferred form herein shown and described, my invention comprises a supporting framework 9, and a chair seat 10 hinged at one side thereof as at 13. The chair seat 55 in the present case comprises a seat 11, arms 12', and a back 12 forming an integral struc-

ture. This chair seat is box-like in form and is provided with a compartment 14 adjacent to the back portion thereof and adapted to provide storage space for a pillow. 60 Adapted to be housed within the framework and below the seat in its closed position is a sectional spring mattress comprising a rear section 15, an intermediate section 16 pivoted thereto as at 30, and a front section 17 65 pivoted to the intermediate section as at 31. Adjacent to the rear of the section 15 at each side thereof as at 18' are pivoted a pair of hangers 18 also pivoted to the seat as at 19. The sectional mattress is supported adjacent to the front side of the framework 9 by means of a pair of standards or members 20 secured thereto, and to which are pivotally connected the sections 16 and 17 at their juncture point 31. 75

In order to support the front section in its open and unfolded position, I provide at each side thereof a movable leg 21 pivoted to the section 17 and pivotally connected to a movable link 22, connected to the intermediate section 16. When unfolding the sections, it is necessary to provide means for positioning the intermediate and rear sections in prolongation or alinement with each other and in order to accomplish this, I provide a lever 23 pivoted at 23' to each side rail of the front mattress section 17 and pivotally connected to a depending member 24 rigidly secured to the rear section substantially at its pivotal point of connection 90 with the intermediate section. It will thus be seen, referring to Fig. 5, that each joint 30 is substantially in the form of a toggle joint controlled by a lever 23, which, as will be readily observed, is further controlled 95 in the opening and closing of the bed by the front section 17. Upon unfolding the sections to the position shown in Fig. 4, the lever 23 operates to straighten the toggle joint 30 and is adapted to maintain and lock the sections 15 and 16 in horizontal alinement thereby to prevent the possible collapse of the same upon placing weight thereon. Thus the rear and intermediate sections form substantially a toggle controlled by a single member 23 at each side 100 of the sections, said member connected directly to the front section and controlled thereby. 105

I provide a suitable head rest 25 hinged to 110 the front section 17 and adapted to be moved into the position illustrated in Figs. 3 and 4

by means of links 26 connected to the movable legs 21. Upon folding the sections to the positions illustrated either in Fig. 2 or Fig. 1, the head rest 25 is swung or moved 5 rearwardly as illustrated in Fig. 2, thereby to enable it to be housed within the framework.

In operation, it will be readily observed that my improved folding chair bed is converted into a full-length single bed merely 10 by swinging the seat 10 rearwardly about the axis of its hinged connection with the supporting structure 9. During this operation the sectional mattress is partially 15 opened and is lifted or elevated to a position enabling the sections to be unfolded with great ease and facility. As the chair seat is swung rearwardly, the section 15, due to the fact that it is suspended adjacent the 20 rear end by means of hangers 18 pivoted thereto, and to the bottom of the seat, is swung rearwardly and upwardly from a substantially horizontal position within the housing to a rearwardly inclined position. 25 The entire mattress is thus elevated and partially opened, and is completely unfolded thereupon by swinging the front section 17 to a horizontal inverted position. By virtue of the links 22, the movable legs 21 are 30 unfolded to the upright supporting position illustrated in Fig. 4 and by virtue of the links 26, the head rest 25 is also positioned as illustrated in Fig. 4. By means of the levers 23, connected to the movable section 35 17, pressure is automatically applied upon unfolding the sections to the toggle joint 30 thereby straightening the same and positioning and maintaining the sections 15 and 16 in horizontal alinement, thereby locking 40 the same in position.

The toggle lever 23 thus operates upon the toggle joint 30 to control the same, and to exert such pressure thereon as will position the same in alinement with pivot 31 45 and pivot 18', thus exerting endwise pressure upon the toggle links formed by the side rails of sections 15 and 16 (see Figs. 4 and 5), and as a result shifting the inner section 15 rearwardly.

50 It will be observed that I have provided a very simple but effective construction, wherein a sectional mattress or bed frame is connected to the supporting framework 9 at the point of connection of the front and intermediate sections through the medium only of a pair of members 20 rigidly secured adjacent the front of the framework.

It will be further observed that the rear section 15 through hangers 18 is directly 55 supported and suspended independently of the framework through the medium of the seat. By means of these hangers 18, I am able to utilize the weight of the seat for partially elevating and opening the mattress 60 sections, as it will be observed that upon

swinging the seat 10 to the position illustrated in Fig. 2, the weight of the seat is effective through the links 18 to swing the rear section rearwardly and upwardly, and thus elevate the entire mattress. Furthermore, by virtue of the hangers 18, the mattress in open position, is elevated or positioned above the supporting framework, the intervening space 27 being desirable and effective to permit the use of a spring fabric 75 of increased resiliency. To facilitate the manipulation of the folding bed, lost motion slots 28 are provided in the hangers 18, and lost motion slots 29 are provided in the toggle or locking levers 23, thus producing a 80 desirable and increased flexibility in the operation of the various inter-connected parts during the opening and closing of the sectional mattress. The hanger links 18 are detachably connected in any suitable manner 85 to the seat whereby the same may be disconnected therefrom and the section 15 swung back on its pivots 30 to permit access to the rear of the supporting framework and the compartment 14. 90

In the folded or closed position of the sectional mattress, or in the position illustrated in Fig. 2, the intermediate section 16 is positioned at right angles to the outer and inner sections, thus providing space therebetween 95 for the mattress or bed clothes 31.

From the foregoing it will be seen that by means of the improved organization of the several parts, it is not necessary, in order to open or close the bed, to handle the combined weight of the heavy, usually upholstered or tufted seat and the sectional bed with its bedding. That is to say, in manipulating the structure, the seat is first swung to the rear of the framework to rest upon 100 the floor, thus acting as a lever to partially raise or elevate the sectional mattress from its housed position within the framework and supporting body of the chair. The weight of the seat, upon swinging it rearwardly beyond the vertical plane through its axis, operates thereupon to elevate the sectional mattress, thereby counterbalancing the weight of the mattress at this time and facilitating quick and easy manipulation of 105 the parts with a minimum of effort. Subsequent to this the sectional mattress is unfolded and completely opened merely by grasping and swinging the forward or front section which, due to its single pivotal connection adjacent to each side at the front of the framework, acts with the toggle lever 23 as a lever to position the rear and intermediate sections in alinement with the front section. Thus the necessity of handling any 110 considerable weight is eliminated, and as a result the entire structure can be easily manipulated by a child or a woman. 115

In the opening of the structure the seat is thrown to the rear or in one direction to 120 125 130

rest upon the floor while the front section is thereupon shifted to the front or opposite direction, so that by reason of the simple connection between the parts the seat and the front section of the bed are effective, with the exercise of but little effort, to operate, move, and control all the other parts of the structure. It will also be observed that there is a minimum of connections and levers 10 in this improved structure since the sectional mattress is pivotally connected with the framework solely by a pair of standards or upright members, and is connected with the seat solely by means of a pair of 15 hangers, these two connecting means constituting the sole means of supporting the entire sectional mattress relatively to the framework and the seat.

Heretofore convertible structures having 20 a seat and arms and a sectional mattress adapted to be folded and unfolded have been constructed so that the seat only is shifted, the arms being rigid with the supports, and as a result the effective width of the mattress is restricted to a width somewhat less 25 than the width of the seat alone. By virtue of my construction however wherein the entire upper part of the chair including seat, arms, and back is swung rearwardly, 30 greater space is available within the framework for the sectional mattress and the latter may thereby have an effective width greater than the width of the seat and substantially or approximately as great as 35 the width of the seat and arms or the supporting framework.

It will be seen that the foregoing structural features are highly important in the present invention, wherein a three-section 40 mattress is provided and adapted to be unfolded to form a full length bed in the direction of unfolding, and transverse of the individual sections, for it is thereby possible to house a full length bed within a structure, such as a chair, having less front width than the full length of the bed when unfolded, and at the same time utilize the greatest 45 width possible of the framework. Hence, the framework, so far as the matter of 50 utilization of the front width thereof is involved as compared to other structures heretofore made, is reduced in the present instance materially without reducing the effective width of the bed.

55 Although I have described a preferred embodiment of my invention, it will be understood that I do not limit myself to the exact details of construction hereinbefore described, but may make such changes as 60 come within the scope of the appended claims.

I claim as my invention:

1. In a folding chair bed, the combination 65 of a supporting framework, a chair seat hinged to one side of said framework for

swinging movement to the rear thereof, a sectional spring mattress housed within said framework and openable to form a full-length bed in the direction of its length and including a rear section and a front section, 70 said sectional mattress being supported on the framework independently of the rear section, and hangers pivotally suspending the rear section from the seat, whereby upon swinging the seat to its open position the 75 sectional mattress is lifted into position to be unfolded thereby to permit the front section to be swung in a direction opposite to the direction of movement of the seat thereby to open the bed. 80

2. In a folding chair bed, the combination of a supporting framework, a swinging seat hinged to one side of said framework, a sectional bed frame pivotally connected to the opposite side of said framework and adapted to be housed therein, means comprising a pair of hangers connecting the seat with the rear section of said bed frame and effective to shift the bed frame upon the rearward swinging of the seat into position to permit 90 the bed frame to be unfolded and also effective to support the entire weight of the rear of the bed frame from the seat when the same is unfolded.

3. In a folding chair bed, the combination 95 of a framework, a swinging seat hinged to one side of said framework, a sectional mattress housed within the framework, said mattress having only one point of connection at each side thereof with the framework, 100 and a single means of connection at each side thereof with the seat.

4. In a folding chair bed the combination of a framework, a rearwardly swinging seat, a three-section mattress adapted to be 105 housed within the framework, said entire mattress having only three means of support at each side and including means adjacent to the front of the framework about which the mattress is adapted to turn when 110 folding and unfolding the same.

5. In a folding chair bed, the combination of a framework, a swinging seat hinged to one side of said framework, a sectional mattress housed within the framework, said 115 mattress having only one means of connection at each side thereof with the framework, and a single means of connection at each side thereof with the seat, such connection with the seat being effective to shift the mattress into position to be unfolded and to suspend the rear of the sectional mattress from the seat when unfolded, and also effective to support the entire weight of the rear of said mattress. 120

6. In a folding chair bed, the combination of a supporting framework, a swinging seat hinged to one side of said framework, a sectional mattress adapted to be housed within the framework upon the closing of the seat 130

and to be partially lifted from the framework in readiness to be unfolded upon the opening of the seat, said sectional mattress when unfolded having the rear section thereof suspended from the seat and being supported by the framework independently of the rear section, the folding section of the mattress swinging into an open position in a direction opposite to that in which the seat is swung.

7. In a folding chair bed, the combination of a supporting framework, a swinging seat hingedly connected to said framework, a sectional mattress adapted to be housed within the framework upon the closing of the seat and to be partially lifted from the framework in readiness to be unfolded upon the opening of the seat, said sectional mattress having the rear section thereof directly supported independently of the framework through the medium of the seat only, and having a single pivotal connection at each side thereof with the framework, whereby upon swinging the seat rearwardly the weight thereof at a predetermined point will be effective by lever action to elevate the sectional mattress to a partially open position.

8. In a convertible bed, the combination of a supporting framework, a movable seat connected thereto, a foldable sectional mattress adapted to be housed in said framework, the rear section and the section adjacent thereto forming substantially a toggle, and a single means connected to a section for operating said toggle thereby to impart endwise movement to the rear section only.

9. In a folding chair bed, the combination of a framework, a seat hingedly connected to one side thereof, a sectional mattress comprising a front and a rear section adapted to be housed therein, said sectional mattress being pivotally supported independently of the rear section solely adjacent to the opposite side of said framework, means for suspending said sectional mattress from the seat and comprising a pair of hangers pivoted to the seat and to the rear section, whereby upon swinging said seat rearwardly, the weight thereof will be effective to elevate said sectional mattress to a partially open position in readiness to be unfolded.

10. In a folding chair bed, the combination of a framework, a seat hingedly connected to one side thereof, a sectional mattress comprising a front and a rear section adapted to be housed therein, said sectional mattress being pivotally supported independently of the rear section solely adjacent the opposite side of said framework, means for suspending said sectional mattress from the seat and comprising a pair of hangers pivoted to the seat and to the rear section, whereby upon swinging said seat rearwardly, the weight thereof will be effec-

tive to elevate said sectional mattress to a partially open position in readiness to be unfolded, and means automatically operative upon unfolding said mattress to position the intermediate and inner section in 70 prolongation with each other.

11. In a folding chair bed, a supporting framework, a swinging seat hinged to one side thereof, a sectional mattress comprising a front, rear and intermediate section pivotally connected together and supported when unfolded by the framework solely at the point of connection of the front and intermediate sections, the rear section thereof having a single means of connection at each 75 side with the seat, and means automatically operative upon unfolding said sectional mattress to position the intermediate and inner sections in prolongation with each other.

12. In a folding chair bed, the combination of a supporting framework, a swinging seat hinged thereto, a foldable mattress having only one means of connection at each side with the framework, and a single link connection at each side with the seat.

13. In a folding chair bed, the combination of a supporting framework, a swinging seat hinged thereto, a foldable mattress having, when unfolded, solely one means of support at each side upon the framework, 95 and a single link connection at each side with the seat, the construction being such that upon unfolding the bed the weight of the seat counterbalances the weight of the mattress.

14. The combination of a supporting framework, a rearwardly swinging seat hinged thereto, a sectional mattress normally housed within the framework and including a rear section shiftable from a position within the framework toward the rear of the framework when the mattress is unfolded, said rear section in unfolded position extending at least as far as the rear of the framework.

15. In a folding bed, the combination of 110 a supporting framework, a swinging seat hinged thereto, a foldable sectional mattress adapted to be housed therein, the rear and intermediate sections of said mattress forming substantially a toggle, and means for 115 operating said toggle to impart endwise movement to one of said sections only.

16. In a folding bed, the combination of a supporting framework, a swinging seat hinged thereto, a foldable sectional mattress 120 adapted to be housed therein, the rear and intermediate sections of said mattress forming substantially a toggle, and means controlled by the front section and operative substantially at the juncture point of 125 said rear and intermediate sections for operating the toggle to impart endwise movement to one of said sections only.

17. The combination of a supporting framework a swinging seat hinged thereto,

a sectional mattress normally housed within the framework and including a rear section shiftable from a position within the framework toward and beyond the rear of the framework when the mattress is unfolded and means for supporting the mattress.

18. The combination of a supporting framework, a rearwardly swinging seat hinged thereto, a sectional mattress normally housed within the framework and including a rear section shiftable from a position within the framework to the rear part of the framework when the mattress is unfolded, said mattress including self-locking means for maintaining the same in its unfolded position.

19. The combination of a supporting framework, a swinging seat hinged thereto, a sectional mattress normally housed within the framework and comprising front, rear and intermediate sections, said rear and intermediate sections forming substantially a toggle, and means for controlling said toggle and effective upon unfolding said mattress to impart endwise movement to the rear section only, said means being effective to lock the mattress in its unfolded position.

20. The combination of a supporting framework a rearwardly swinging seat hinged thereto and comprising as an integral structure a seat, a back, and side arms, a sectional mattress having a width as great as the width of the seat normally housed within the framework and including the rear section shiftable from a position within the framework to a position above the framework when the mattress is unfolded, and means for supporting the mattress.

21. The combination of a supporting framework a rearwardly swinging seat hinged thereto and comprising as an integral structure a seat, a back, and side arms, the back being adapted to rest upon the floor in its tilted position, a sectional mattress having a width greater than the effective width of the seat normally housed within the framework and including a rear section shiftable from a position within the framework toward the rear of the framework when the

mattress is unfolded, and means for supporting the mattress.

22. The combination of a supporting framework a swinging seat hinged thereto and comprising a seat, a back, and arms, a foldable mattress having a single point of connection at each side with the framework and a single link connection at each side with the seat, said seat constructed to rest upon the floor in its tilted position and forming the sole support for the rear end of the mattress.

23. A convertible chair bed comprising a framework, a foldable mattress adapted to be housed therein and comprising three sections only, a rearwardly swinging seat hinged to the framework, the several sections of said mattress being constructed to form when unfolded a full length bed in the direction of unfolding and transversely of the width of the several sections.

24. A convertible chair bed comprising a framework a foldable mattress adapted to be housed therein and comprising three sections only, a rearwardly swinging seat hinged to the framework, said mattress being adapted to be unfolded to form a full length bed in the direction of unfolding, said direction being transverse to the front width of said seat, said seat comprising as an integral structure a seat, a back and side arms, and said mattress having a width as great as the width of the seat thereby to permit utilization of substantially the greatest possible front width of the framework.

25. A convertible chair bed comprising a framework, a foldable mattress adapted to be housed therein and comprising three sections only, a rearwardly swinging seat hinged to the framework, said mattress being adapted to be unfolded to form a full length bed in the direction of unfolding, said rear section having an endwise shiftable movement at least as far as the rear of the framework upon unfolding the mattress.

Signed at 1822 Park Row Building, New York city, New York, this 20th day of December, 1920.

JOSEPH LUPPINO.
